UNITED STATES PATENT OFFICE.

ROGERS A. ABBOTT, OF WORCESTER, MASSACHUSETTS, ASSIGNOR TO
HIMSELF AND GUSTAVUS W. INGALLS, OF SAME PLACE.

IMPROVEMENT IN REEDS FOR MELODEONS.

Specification forming part of Letters Patent No. **82,268**, dated September 22, 1868.

To all whom it may concern:

Be it known that I, ROGERS A. ABBOTT, of the city and county of Worcester, and State of Massachusetts, have invented a new and useful Improvement in Reeds for Melodeons, or other instruments of like nature; and do hereby declare the same to be fully described in the following specification and represented in the accompanying drawings, of which—

Figure 1 is a top view; Fig. 2, longitudinal section of a reed-socket plate and its reed as provided with my invention. Fig. 3 is an edge view of the reed preparatory to being riveted to the socket-plate.

The head, or that part of the reed which is fastened to the socket-plate, has, prior to my invention, been made with a plane-surfaced bottom. In consequence of this it has been found that after the head has been riveted to the socket-plate, such head was sprung or bent down, so as to throw its edges more or less up from the plate. When this is the case a vibration of such edge or edges on the plate is apt to ensue during sounding of the reed, the

same being detrimental to its tone, and often productive of an unpleasant sound. As a remedy for the evil, I arch or curve the head of the reed-plate before it is riveted to the socket-plate.

In the drawings, the reed is shown at A, *a* being its rectangular head, and *b* its tongue. The socket-plate is shown at B. The head *a* is also exhibited as crowned or arched a little lengthwise where it rests on the plate B, the same causing it to be supported on the plate at the extremes of the arch. The head is thus caused to rest on the plate, in or about in two lines only, and when riveted thereto, in which case no vibration of the head on the plate can take place when the reed is sounded.

What I claim as my invention is—

The improved reed, as made with an arched head, as and for the purpose specified.

ROGERS A. ABBOTT.
